JAR CLAMP

Charles H. McColgan, Cuyahoga Falls, Ohio

Application August 25, 1934, Serial No. 741,475

6 Claims. (Cl. 81—3.3)

The present invention relates to jar holding devices and the primary object of the invention is to provide a jar clamp having a construction whereby a jar may be rigidly held against rotation so as to permit either placing or removal of a threaded closure cap or cover thereon.

A further object of the invention is to provide a jar clamp wherein the base portion of a jar will be automatically gripped to prevent turning of the jar when either placing or removing the cover therefrom, and automatically released by a slight turn of the jar.

A further object is to provide a device of this character which is of substantially flat formation so as to permit storing away of the device in a comparatively small space when not in use, and which device when in use, co-acts with an edge of a table top or similar flat surface in a manner to hold the device in position for use.

A further object is to provide a jar clamp which is reversible to adapt the clamp for use in either placing or removing the jar top, and which clamp may be very economically manufactured owing to its particular construction.

A still further object is to provide a device of this character which will not become heated to any appreciable extent when used for a considerable length of time for holding jars filled with hot commodities and one wherein both hands of the operator are free to apply the cover direct, or to use a suitable gripping device for tightening the cover.

Other objects and advantages of the invention will be apparent from the following detailed description, taken in connection with the accompanying drawing forming a part of this specification and in which drawing:—

Figure 1 is a perspective view of the improved jar clamp or holder in position for use upon a table top or the like and showing the jar held thereby in a manner to permit placing of a threaded cover thereon.

Figure 2 is a perspective view showing the jar clamp reversed or turned over as when being used for removing a threaded cover from the jar.

Figure 3 is a central longitudinal section thru the jar clamp in a plane parallel to the major plane of the clamp.

Figure 4 is a longitudinal section on the line 50 4—4 of Figure 3.

In the drawing, and wherein like reference characters designate corresponding parts thruout the several views, the letter A designates as a whole the improved jar clamp or holder adapted 55 for positioning upon a flat surface such as a table

or bench top as indicated at B. The letter C designates a jar having a screw threaded upper end for receiving a screw threaded closure cap or cover D.

The jar clamp A comprises a thin, broad, flat, rectangular-shaped base or main body member 5 which is preferably formed of wood and having the grain of the wood running lengthwise of the body member. Secured along the rear edge of the body member 5 is a T-shaped cleat 6 having a tongue and groove joint with the member 5 and having its edges extending flush with the opposite faces of the body member. The body member 5 is formed with an elongated opening 7 having its major dimension extending lengthwise of the body member midway between the side edges thereof. The rear end portion of the opening 7 is of semi-circular shape in formation as indicated at 8 and terminates inwardly of the rear edge of the body member, while the forward end portion 9 of the opening preferably has its side edges converging toward the front or forward edge of the body member. The forward end of the opening 7 opens at the front edge of the body member providing a substantially U-shaped body member, and this arrangement of having the opening extend to one end of the body member allows for ready cutting of the opening 7 as upon a band saw. The semi-circular end portion 8 of the opening 7 provides a jar receiving portion and is preferably lined with a gripping strip 10 of corrugated rubber or any other suitable material capable of producing a gripping action upon the base portion of the jar C so as to resist turning the jar when the jar is urged into engagement with the strip.

Provided with a tongue and groove joint connection with the front edge of the body member 5, is a T-shaped holding strip 11 providing stop flanges 12 projecting beyond each flat face of the body member so as to engage against an edge of the table or bench top B when the jar clamp is in either of the reverse positions as shown in Figures 1 and 2. The holding strip 11 extends along the forward end of the body member 5 and bridges the open end of the opening 7. Retaining screws 14 are threaded thru the end portions of the holding strip 11 and into the arm portions 13 of the body member 5 at opposite sides of the opening 7 and as will be observed in Figure 3, the converging forward end portion 9 of the opening provides substantial portions at the forward end of the body member arms 13 for receiving the retaining screws 14.

Thus it will be seen that the cleats 6 and hold-

ing strip 11 strengthen the ends of the body member and prevent warping. The holding strip 11 aside from forming a connection for the forward end of the arm portions 13 also forms stop flanges 5 which when engaging an edge of the top B act to prevent turning of the clamp.

Arranged in the forwardly converging portion 9 of the opening 7 is a cam member or jaw 15 which is also preferably formed of wood and has 10 a thickness equal to the thickness of the body member 5. This cam member 15 is pivoted at its forward end upon a web member 16 formed of a suitable gauge sheet metal and secured to extend across the forward end of the opening 7 mid- 15 way between the upper and lower faces of the body member. This sheet metal web member 16 is adapted to be held in position thru attachment of the holding strip 11 to the body member 5, and as shown more clearly in Figure 4 is disposed 20 midway between the opposite flat faces of the body member. The tongue or stem of the T-shaped holding strip 11 is longitudinally slotted at its central portion as at 17 to receive the forward edge of the web 16, while the arm portions 25 13 are each slotted adjacent the opening portion 9 as at 18 for receiving end portions of the web. These slots 18 have their base edges converging rearwardly for engagement with correspondingly converging edges on the web 16, whereby rear- 30 ward movement of the web is limited. Forward movement of the web member is limited thru engagement with the base of the slot 17, and as will be noted in Figure 3 the end of the web members terminate inwardly of the retaining screws 35 14. The cam 15 is slotted as at 19 for receiving the web 16 whereby the cam may be pivoted upon the web as by a pivot pin or screw 20 and has swinging movement transversely of the opening 7 between the arm portions 13.

40 The head or free end of the cam 15 is formed with a cam edge 21 which is preferably covered with a strip of corrugated rubber or the like 22 adapted to frictionally engage the jar C and urge the jar toward the semi-circular shaped end 8 45 of the opening 7. Each face of the cam 15 adjacent the free end of the cam is provided with a recess 23 providing finger grips for swinging the cam into engagement with the jar. The cam 15 is also preferably provided on opposite sides with 50 the markings "on" and "off" as shown in Figures 1 and 2 for indicating the proper side of the clamp to be disposed uppermost. When the marking "on" appears as in Figure 1, the clamp is in a position for applying the cap, and when 55 the marking "off" is exposed as in Figure 2, the clamp is in its proper position for removing the cover from the jar.

In use of the device for applying the cap D to the jar C, the device is placed upon a table top 60 or other flat surface in the position shown in Figure 1 with one of the stop flanges 12 engaging upon the edge of the table top. The jar is then placed in the rear semi-circular shaped end of the opening 7 and by placing one's finger in the 65 recess 23 the cam 16 is moved into engagement with the jar. The cap D may then be screwed on the jar and when the cap is turned tight, any tendency of the jar to rotate in a clockwise direction, considering Figure 3, will swing the free end 70 of the cam 15 toward the left and firmly press the jar against the gripping strip 10 so that the jar is rigidly held against rotation. When removing the cover from the jar, the device is placed in the position shown in Figure 2 whereby any 75 tendency of the jar to rotate in a counter-clock-

wise direction causes the cam to more firmly grip the jar and prevent rotation thereof. Thus it will be seen that by merely reversing or turning the device, the cover may either be placed or removed from the jar and the operator has both hands free to apply the turning force to the cap. While if so desired, the device may be clamped to the table top, it has been found in use, that the device will work very satisfactorily by being simply laid on a flat shelf or table top and held 10 in place during use by the stop flanges 12. 5

It will be observed that the device grips a jar about the base portion of the jar where there is little, if any, danger of breaking the jar by the gripping action of the device upon the jar. When 15 desiring to release the jar from the holding device it is merely necessary to impart slight turning to the jar, say in a counter-clockwise direction considering Figure 3, to automatically swing the cam 15 toward the right and release the jar. 20

While the device has been described as preferably being constructed in its major portions of wood because of neatness and low heat conduction qualities it is to be understood that various other forms of material may be employed in the 25 construction of the device.

Changes in the shape, size and arrangement of parts may be made to the form of invention herein shown and described, without departing from the spirit of the invention or the scope of the 30 following claims.

I claim:

1. A jar clamp comprising a flat body member having an elongated opening therethru, a pivoted cam member in one end of the opening for gripping engagement with the base portion of the jar inserted into the other end of the opening from either face of the body member, and a holding strip along one edge of the body member and projecting beyond each face thereof. 40

2. A jar clamp comprising a flat body member having an elongated opening therethru formed at one end with a semi-circular jar receiving portion, a pivoted cam member in the other end of the opening and having a cam edge at its free end 45 co-acting with said jar receiving portion for gripping a jar therebetween, and a holding strip secured along one edge of the body member and providing stop flanges projecting beyond the plane of each face of the body member. 50

3. A jar clamp comprising a flat wooden body member having an elongated opening therethru and opening at the front edge of the body member, a holding strip secured along the front edge of the body member and providing stop flanges 55 projecting beyond each face of the body member, a web member retained in position across the forward end of the opening midway between the opposite faces of the body member, and a cam member pivoted on said web member for swing- 60 ing movement laterally in said opening.

4. A jar clamp comprising a flat wooden body member having an elongated opening therethru, a holding strip along the front edge of the body member and providing stop flanges projecting beyond each face of the body member, a sheet metal web member retained in position across the forward end of the opening by said holding strip, a cam member having a slotted end for receiving said web member, and a pivot connecting the cam 70 member to said web member, said cam member having a thickness no greater than the thickness of said body member.

5. A jar clamp comprising a flat body member having an opening therethru for receiving at one 75

end, the base portion of a jar, a thin web member extending across the other end of the opening midway between opposite faces of the body member, a cam member slotted at one end to receive the web member and provided at its other end with a cam edge, a pivot pin pivotally connecting the cam member to the web member, and a finger gripping recess provided on each side of the cam member.

6. A jar clamp comprising a flat, U-shaped wooden body member providing a pair of spaced apart arms forming an opening, a holding strip connecting the free ends of said arms and projecting beyond opposite faces of the body member, and a cam member pivotally mounted between the arms at one end of said opening. 5
